UNITED STATES PATENT OFFICE.

WILLIAM J. SPILLMAN, OF PULLMAN, WASHINGTON, ASSIGNOR OF ONE-HALF TO JOHN W. STEARNS, OF PULLMAN, WASHINGTON.

CHEESE-CUTTER.

SPECIFICATION forming part of Letters Patent No. 701,098, dated May 27, 1902.

Application filed May 18, 1901. Serial No. 60,846. (No model.)

To all whom it may concern:

Be it known that I, WILLIAM J. SPILLMAN, a citizen of the United States, and a resident of Pullman, in the county of Whitman and State of Washington, have invented a new and Improved Cheese-Cutter, of which the following is a full, clear, and exact description.

This invention relates to a device for carrying a cheese and facilitating the work of slicing it in regularly-formed pieces.

The device is particularly adaptable for use by retail merchants.

This specification is a specific description of one form of the invention, while the claims are definitions of the actual scope thereof.

Reference is to be had to the accompanying drawings, forming a part of this specification, in which similar characters of reference indicate corresponding parts in all the views.

Figure 1 is a side view of the invention. Fig. 2 is a plan view thereof. Fig. 3 is a sectional plan view looking down from the line 3 3 of Fig. 1, and Fig. 4 is a section on the line 4 4 of Fig. 3.

The device comprises an annular base *a*, having a spider *a'* extending across it and provided with a centrally-located pin *a²*, on which is arranged a circular table *b*, adapted to carry the cheese and capable of turning freely on the base *a*.

a³ (see Fig. 3) indicates small carrying-wheels on which the edges of the table *b* rest and by which the table is supported from gyration.

The spider *a'* is dropped below the upper edge of the frame *a*, as indicated by the dotted lines in Fig. 1, and the frame *a* is formed with a segmental reduced portion *a⁴*, in which fits the free end of a radially-disposed arm *c*, pivoted upon the pin *a²* and extending outward over a segmental scale *e*, held rigidly on a ledge *a⁵*, formed, preferably, integral with the base *a*, directly adjacent to the reduced portion *a⁴*. The free end of the arm *c* carries two lugs *c'*, and between these lugs is pivoted a dog *d*, which has a serrated surface *d'* and which when thrown up in the position shown in Fig. 4 engages this surface with the edge of the table *b*, thus fastening the table to the arm *c* and permitting the table to be turned over the base *a*. It will be seen that

by manipulating the dog *d* the table may be turned around with a step-by-step movement. In order that the movement of the table may be adjusted to allow it to be turned the requisite distance to permit a piece of cheese of a predetermined value to be cut from the cheese carried by the table, the scale *e* is provided with an adjustable stop *e'*, secured thereto by the set-screw *e²*. By adjusting the stop on the scale the movement of the arm *c*, and consequently the table *b* when locked to the arm, can be adjusted to permit a piece of cheese of any desired value to be cut.

Mounted on the base *a* are two outwardly-projected stanchions *f*, between which extends a cross-head *g*, having recessed ends *g'*, adjustably fitted on the stanchions. The cross-head *g* carries a superstructure *g²*, on which is fulcrumed a lever *h*, connected by links *h'* with a knife-blade *i*. This knife-blade passes through a slot in the cross-head *g* and has its outer edge guided in a groove in the adjacent stanchion *f*. The inner edge of the knife *i* is guided in a stanchion *g³*, rising from the cross-head *g* and located directly over the center of the table *b*. The knife *i* is of a width greater than the distance the cross-head *g* is above the table, so that when the knife is lowered into engagement with the table its upper portion will be in engagement with the stanchion *g³* and its inner edge firmly supported thereby. By arranging the stanchion *g³* on the cross-head *g* the space below the cross-head between the stanchions *f* is left free, so that a cheese intact can be readily placed upon the table. The hand-lever *h* is preferably constructed of sheet-metal straps, which are separated from each other at the point *h²*, so as to receive the stanchion *g³* as the lever moves downward. It will be observed that by turning this knife down on the table *b* and should a cheese be on the table the cheese will be cut radially from its center outward to its periphery.

In operation, the cheese having been placed on the table and the arm *c* locked to the table by the dog *d*, the stop *e'* is adjusted on the scale *e* according to the value of the piece of cheese to be cut and then the table is

turned by the said dog until the arm *c* rests against the stop or the opposite end of the scale, according to the direction the table is turned, when the knife is operated by the lever *h* to cut the cheese.

Various changes in the form, proportions, and minor details of my invention may be resorted to without departing from the spirit and scope of my invention. Hence I consider myself entitled to all such variations as may lie within the scope of my claims.

Having thus described my invention, I claim as new and desire to secure by Letters Patent—

- 15 1. In a cheese-cutter, a support, a revoluble table mounted on the support, a segmental scale carried by the support, an arm mounted on the pivot of the table and extending over the scale, a stop adjustably secured on the scale and between which and the end of the scale the arm is adapted to be moved to permit the table to be turned a predetermined distance at each movement of said arm, and a dog pivoted to the outer end of the arm and 25 having a serrated face adapted to engage the table to lock the arm thereto, as set forth.
2. In a cheese-cutter, a base provided with stanchions on its upper face, a cross-head mounted on the stanchions above the base and 30 provided at its center with a stanchion projecting from its upper face, and a reciprocating knife having guided movement on the stanchion of the cross-head and one of the stanchions of the base, as set forth.
- 35 3. In a cheese-cutter, a base provided with stanchions projecting from its upper face, one of the stanchions being longitudinally grooved, a slotted cross-head adjustably secured on the stanchions and provided at its

center with a longitudinally-grooved stanchion on its upper face, a knife mounted in the grooves of the said stanchions and the slot of the cross-head, a pivoted lever on the cross-head, and a link connecting the lever with the knife, as set forth. 40

4. A cheese-cutter, comprising a base, provided with stanchions, a cross-head adjustably supported on the stanchions above the base, and provided with a stanchion at its center, a reciprocating knife having guided 50 movement in one of the stanchions of the base and the stanchion of the cross-head, a revoluble table mounted on the base, a scale carried by the base, an adjustable stop on the scale, and an arm connected with the base and extending over the scale, as set forth. 55

5. A cheese-cutter, comprising a base provided with stanchions on its upper face, a slotted cross-head adjustably mounted on the stanchions and provided at its center with a stanchion, a reciprocating knife working in the slot of the cross-head and having guided movement in the stanchion of the said cross-head and one of the stanchions of the base, a revoluble table mounted on the base, a scale 60 carried by the base and provided with an adjustable stop, an arm mounted on the pivot of the table and extending over the scale, and means for locking the arm to the table, as set forth. 65

In testimony whereof I have signed my name to this specification in the presence of two subscribing witnesses.

WILLIAM J. SPILLMAN.
